UNITED STATES PATENT OFFICE.

GEROLT GIBSON, OF ST. LOUIS, MISSOURI.

NUT-LOCK.

SPECIFICATION forming part of Letters Patent No. 492,672, dated February 28, 1893.

Application filed September 29, 1892. Serial No. 447,315. (No model.)

To all whom it may concern:

Be it known that I, GEROLT GIBSON, a citizen of the United States, residing at St. Louis, State of Missouri, have invented certain new and useful Improvements in Nut-Locks; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to that class of mechanical contrivances or devices termed nut-locks, primarily, as its name denotes, for locking nuts upon their bolts as against accidental displacement or unscrewing of the nut from any jarring action, as in the case of an engine or train of cars passing over its rails, or from other cause, or when used with their bolts for any other purpose or under any other circumstances, and to these ends the invention consists in the novel combination and construction of parts substantially as herein-after more fully disclosed and pointed out in the claims.

In the accompanying drawings:—Figure 1 is a perspective view of my improved nut-lock, showing one way of applying it for use, among others of which it is capable. Fig. 2 is a similar view of the several parts of my nut-lock dissociated and relatively disposed. Fig. 3 is an inverted perspective view of the locking nut. Figs. 4 and 5 are modifications of my invention.

In carrying out my invention, I employ a bolt A, a notched or ratchet-faced nut B, and a washer C. The bolt A has a longitudinal groove or channel α traversing, preferably, the greater portion of its length. The ratchet-face of the nut is composed of a series of notches or steps b , having continuously gradually sloping or inclined bottoms b' with their maximum depressions terminating at perpendicular walls b^2 , forming in part said notches, and these notches face inward toward the surface of the rail or article to be bolted. The washer C is struck up preferably, of spring metal, into disk or other form and has projecting transversely toward the axis of the bolt inward from a point coincident with its

outer edge or circumference, a stop or detent c , arranged in a radial slot c' , produced in the body of the washer, and having its termini at 55 the outer edge or circumference of the washer and the central bolt-hole thereof. The slot c' , in permitting the detent c to sink flush with the washer, as it does as the nut engages the detent, instead of standing in a plane 60 above the washer, lessens the strain on the detent and the spring and permits the nut to be brought jam against the washer, the advantages of which are apparent.

The stop or detent c is formed at its outer 65 end integral with, or in continuation of a spring c^2 , itself preferably integral with the washer C, being stamped therefrom in the form of a segment in this instance following the outer edge-contour or circumference of 70 the washer, but inclined or curving outward toward, and at, its outer detent or stop-carrying end, to cause the stop or detent to stand a short distance above the washer to cause it to automatically engage the notched or ratchet-face of the nut as the latter is turned or 75 screwed home.

The plate or washer C has a spline-like projection or tongue c^3 extending into its bolt-hole and engaging the longitudinal groove or 80 channel α of the bolt A, to prevent the turning of the washer independently of the bolt, the bolt, itself, being prevented from turning or having axial movement by forming thereon the usual angular portion or shoulder α^2 85 engaging a corresponding recess in the part through which the bolt passes. It will therefore be seen that, with the washer and the nut initially in position on the bolt, upon turning the nut in the required direction a 90 short distance, its ratchet or notched face will be engaged by the detent or stop and the latter will alternately be retracted and projected at each turn of the nut, during such engagement, the detent or stop thus projecting or 95 springing into each notch and providing for the retention of the detent, in any, or whichever, one of the notches that may be stopped opposite the detent.

In order to release the nut it is only necessary to press down or inward upon the detent and hold it until the nut has been turned in the reverse direction sufficiently to become disengaged from the detent. It will be also

observed that, while the perpendicular wall of the coincident notch of the nut, which the 5
detent has to pass or be disengaged from before release, effectually prevents the reverse
movement of the nut, the notched or ratchet
face of the nut is not acted upon by spring
pressure to hold it in place, nor yet required
to have any part of its surface specially pro-
vided for that purpose, or otherwise, bent up
10 against the nut to secure it in position.

The spring, it will be noticed in my inven-
tion, is used only to project or spring the
detent or stop into the required notch of
the nut, consequently metal possessing but a
15 minimum amount of elasticity, and no great
strength of spring is needed, and the spring it-
self is subjected to the least possible resist-
ance, therefore the detent, with its spring
does not require premature renewal, and a
20 great deal of time and attention to keep them
in working order.

My invention also forms both a washer and
a nut-lock at the same time; and the washer
fits tight and flat upon the surface against
25 which the nut pushes or forces it, meeting
said surface at all points; and the nut bears
flat against the washer on all sides, thus leav-
ing no longitudinal waste space between the
30 nut and the washer, and the latter and the
surface against which it rests.

The spring of the detent or stop exerts no
appreciable pressure upon the nut, conse-
quently does not tend to pry the nut off the
bolt, nor exert lateral strain upon, and tend
35 to distort, the threads of the screw bolt.

The spring locking action of the detent or
stop produces a clicking action upon the
ratchet or notched face of the nut as the lat-
ter is screwed upon the bolt and therefore
40 gives notice when the locking point has been
reached. This feature is, it is obvious, of es-
pecial advantage in screwing on nuts in per-
ilous positions, as at difficult places on bridges
45 and other elevated points, shortening up the
time consumed in locking them, the nut re-
quiring but a few turns to effect the clicking
action between it and the detent, signaling
the locking of the nut. The spring is low down
50 and well out of the way of accident or disar-
rangement and is never engaged, and, there-
fore, never subjected to unnecessary compres-
sion and straining, by the nut as it is screwed
home. The detent or stop and its spring be-
ing a continuous or one piece and integral
55 with the washer, can never become displaced
or lost.

In lieu of the tongue c^3 the washer may be
struck up with one or more lips or points
which are embedded in the surface to which
the washer is applied in case such surface 60
should be wood, and in this way prevent the
independent movement or displacement of
the washer.

In the modifications as disclosed in Figs. 4
and 5 instead of extending the slot c' and de-
tent c clear into the bolt-hole of the washer,
they are stopped a short distance away from
said bolt-hole, Fig. 5 also showing the inte-
gral detent and spring in alignment through-
out their length, the washer being elongated 70
or extended for that purpose as shown.

I make no specific claim herein to the pawl
at right angles to its spring, the same being
specifically claimed in my concurrent applica-
tion, filed October 14, 1892, Serial No. 448,883. 75

I claim—

1. In a nut-lock, the combination, with a
nut whose base is provided with a series of
notches or ratchets, of a longitudinally grooved
bolt, and a locking washer or plate having a 80
tongue engaging the groove of said bolt, and
a spring stop or detent, the point of connec-
tion of said stop with its spring and the
spring, itself, being outside of the base of the
nut, substantially as and for the purpose set 85
forth.

2. In a nut-lock, the combination, with a
nut whose base is provided with a series of
notches or ratchets, of a locking plate or
washer having a radial or transverse slot, and 90
a radial or transverse spring-detent or stop
standing above, and in alignment with, said
slot, the point of connection of the stop with
its spring, and the spring, itself, being out-
side of the base of the nut, substantially as 95
and for the purpose set forth.

3. In a nut-lock, the locking-plate or washer,
having a detent or stop standing transversely
to the axis of the bolt and adapted to engage
a notched or ratchet-faced nut, and having 100
its integral spring constituting a segment of
the washer and curved or inclined outward
or upward along the outer edge of said washer,
out of alignment or engagement with said
nut, substantially as set forth. 105

In testimony whereof I affix my signature in
presence of two witnesses.
